Attorney, Agent, or Firm—Scully, Scott, Murphy & Presser

[57] CLAIM

The ornamental design for an indicator for garment hangers, as shown and described.

DESCRIPTION

FIG. 1 is a perspective view of an indicator for garment hangers, showing our new design, the reverse side being a mirror image thereof, the portion of the hanger bar and the numerals shown in broken lines are for illustrative purposes only;

FIG. 2 is an enlarged perspective view of our indicator for garment hangers, the numerals shown in broken lines are for illustrative purposes only;

FIG. 3 is an exploded, enlarged sectional view taken in the direction of line 3—3 of FIG. 1; and,

FIG. 4 is an enlarged transverse sectional view of FIG. 1.
